UNITED STATES PATENT OFFICE.

JULIUS D. BERNSTEIN, OF NEW YORK, N. Y.

NON-SINKABLE LIFE-BOAT.

1,295,843.

Specification of Letters Patent.

Patented Mar. 4, 1919.

Application filed August 7, 1918. Serial No. 248,792.

To all whom it may concern:

Be it known that I, JULIUS D. BERNSTEIN, a citizen of the United States, residing at New York, in the borough of the Bronx and State of New York, have invented certain new and useful Improvements in Non-Sinkable Life-Boats, of which the following is a specification.

This invention relates to non-sinkable metallic boats and consists in the construction and combination of parts hereinafter more particularly set forth and claimed.

In the accompanying drawings:

Figure 1 is a top plan view of a boat embodying my invention, with the top and side covers folded open;

Fig. 2, a transverse section on line 2—2 of Fig. 1;

Fig. 3, a detail transverse sectional view on line 3—3 of Fig. 1;

Fig. 4, a side elevation of my invention with the top and side cover closed;

Fig. 5, a detail transverse sectional view through a part of one side of the boat arranged as in Fig. 4, showing the construction of the bracing tubing, the stationary tubing and the guide rings;

Fig. 6, an enlarged view on line 6—6 of Fig. 1;

Fig. 7, a detail sectional view on line 7—7 of Fig. 1;

Fig. 8, a detail plan view of one of the drums 35 and proximate parts; and

Fig. 9, a detail plan view of one of the toilet seats and its cover, with proximate parts, the casing being in section.

Referring now in detail to the drawings, the double hull of the boat is composed of an outer hull A and an inner hull B, leaving a space between them, the hull A being of relatively thin aluminum, preferably formed of one piece or sheet of metal stamped out, in the form shown to provide two longitudinal compartments 1 divided by a broad flat-topped central longitudinal inverted trough or hollow rib or partition 2 to brace the boat longitudinally and also to receive between its two walls a paddle-wheel 3 (Fig. 1) operated by cranks 4 connected to shaft 5, which passes through suitable stuffing boxes 6 in the walls of said trough 2 and to which the paddle wheel 3 is keyed, the shaft 5 being so positioned

that the paddle wheel 3 will operate on the water in said trough to propel the boat.

Mounted on the top of the said inverted trough 2 are two toilet closets, one of said closets facing, and entered from, each compartment 1, and both of said closets being located at a distance from the paddle wheel. The casing of said closets, including the side walls 7 and top thereof, is in one piece of very thin aluminum, stamped to the shape desired. Said walls are soldered along their bottom edges to the top of inverted trough 2. The top of the casing is integral with one of said side walls 7, but soldered to the edges of the other side walls thereof.

The door 8 is to swing vertically by means of hooks 9 passing around a rod 10 in the top of the closet and is held closed by means of a catch 11.

Each closet is provided with the usual seat and bowl which discharges through a pipe 12^a (Fig. 3) extending down through the top of the trough or rib 2 between the walls thereof into the water.

Horizontal brace plates 13 soldered at each end portion to the lower face of the respective compartments and extending across the trough 2 at numerous intervals brace the boat transversely. One of these plates is illustrated in Fig. 7. Said plates 13 hold in shape and place the open lower end of the hollow partition 2, preventing the edges of its walls from bending inward or outward.

Upright brace bars 14, U-form in plan (Figs. 1 and 8) are attached to the inner hull B (Fig. 2) and provide bearings (Fig. 8) for drums 35 hereinafter described. There are two pairs of these brace bars 14, respectively near the bow and stern of the boat, all of the said bars being within it, but not between the hulls. Spacing and bracing bars 15 are fixed between the two hulls, dividing the intervening space into water-tight compartments, beside strongly bracing the said hulls and especially the inner hull B. The inner hull B is of very thin aluminum, only about half as thick as hull A and is soldered to the top and edges of these bracing bars 15. The water-tight compartments thus formed by said bars 15 between the two hulls insure that if a leak should occur it

would flood only a very small compartment instead of flooding the whole space between the walls of the hulls. It will be observed that the ribs 15 have three functions, bracing the hulls, spacing the hulls and dividing the intervening space into water-tight compartments.

Also, at the rear portion of the trough or rib 2 the rudder post 16, provided with rudder 22, is mounted, its lower end being seated in a bearing block 17 soldered to the upper face of the rear brace plate 13 and has its upper portion journaled in a bearing projecting through the upper wall on top of the inverted trough 2. On the upper end is mounted an arm 18 to steer by, said arm being connected by a pair of steering ropes 18* Fig. 1 to a steering device 19 near the bow of the boat. Aft of this device a seat 20 for the steersman to sit on, is soldered along its lower edges to the top of the trough or rib 2 so as to be watertight at the bottom, also its sides are watertight, it being formed of one piece of aluminum and having its end portions soldered together up the one side of the seat where they overlap. Said seat is provided with a removable top so as to give access from the top to the interior of said seat, and food and water for a reasonable time for one person may be inserted through the opening left on removal of said top.

Also, around the walls of each compartment 1, except adjacent the path of the cranks 4 on the inside wall of each compartment, a series of aluminum seats 23 are arranged. These are preferably arranged in series, divided off from each other by aluminum partitions. The bottom edges of the front and side walls of said seats are soldered to the upper face of the bottom of hull B, the outer sides of the ends being soldered to the walls of hull B, and the top being provided with preferably circular openings, the walls of which are screw-threaded, giving access to the interior of said seats between each respective two partitions. This top is soldered to the tops of said partitions, the top of the front and sides and to the side wall of hull B, thus giving a series of seats forming in their interior watertight compartments for the reception of cans to store food and water for the occupant of each seat respectively. Each opening in the top is adapted to removably receive a screw-threaded closure or cover, which may be provided with a sunken bail or other means giving a grip to turn said cover.

Two ballast tanks 24 (Fig. 6) are located at the rear, one in each compartment 1, between the floors of the hulls A and B and are adapted to be filled with sea-water through a pipe 25 provided with a control valve 26 and extending through the adjacent side wall of trough or rib 2 below the water line.

Located in each tank is a flexible air tight, preferably rubber, bag 27, adapted to be inflated through valve 28 by means of an air pump 29, and of such size that, when inflated, it will completely occupy the interior 70 of its tank.

In case of a rough sea, the ballast tanks may be wholly or partially filled with water, as necessary, by turning the valves 26 in the correct direction, and their weight, when 75 thus filled, will steady the boat, guarding the occupants against *mal de mer*. However, when the boat is to be lifted on a ship it should be as light as possible and for this reason, before being hoisted in the davits, 80 the tanks 24 should be emptied of water, this being accomplished by opening the valves 26 and operating the air pumps 29 to inflate the bags 27 and thus expel the water from the tanks 24 through the pipes 25.

To further stabilize the boat and to guard against sinking or capsizing, I provide two long pontoons 30 arranged to normally lie one on each side of the boat on the water surface. Each pontoon is made of cork and is pivotally connected to the ends of the boat by means of a pair of arms 31, pivotally mounted on the ends of the boat as at 32, each pair of arms 31 being connected to the respective ends of a rod 33 passing through 95 the respective pontoons. Chains 34 connected to the outside of the boat and passed over their respective pontoons 30 and wound on their respective drums 35 keyed on a shaft 36, operated by a slidable handle bar 37 and held against reverse movement by a pawl 38 engaging ratchet 39 hold each of said chains tight, holding said pontoons firmly in normal position.

When the boat is to be carried on a ship 105 the chains 24 are released, freeing the pontoons 30, which are then turned, by means of their pivoted arm connection, up over the top of the boat, where they will not take up so much room transversely and will be less liable to be damaged.

A frame 40 preferably of tubular aluminum is soldered to the top of the composite hull as a frame for the top and side covers. The side cover 41 is preferably formed of a 115 continuous strip of water-proof material provided with windows of flexible transparent material, and fastened along its lower edge to the top edge of the hull of the boat by means of a stripping 42 secured thereto 120 in any suitable manner as by rivets or screws 43.

The top edge of side cover 41 is secured to a tubular aluminum former or brace rod 45 to which hoisting and lowering ropes 52 are 125 connected, running from said rod to a pulley block 46 connected to the frame 40. This cover 41 is also provided with guide rings 47 (Fig. 5) sewed thereto and encircling the respective uprights of the frame 40 to hold 130

said cover close to said frame in either raised or lowered position.

The top cover 48 is fastened to the frame 40 along its longitudinal central line, provided with guide rings 47 encircling the transverse rods of the frame 40 and provided at both side edges with tubular aluminum former or brace rods 53 to which are attached ropes 49 running to pulley blocks 10 attached to said frame 40 so that either side portion of the top cover 48 may be moved out over the eaves 51 of the frame 40, or both may be spread at the same time as desired. By this arrangement the said cover may be 15 raised or lowered as desired, the top remaining folded, or either side of the top, or both sides of the top may be spread and the side cover 41 raised or lowered at the same time, as desired.

20 All parts entering into the construction or fittings of this invention are to be, preferably, of aluminum, on account of its strength and lightness, excepting the side and top covers and the pontoons.

25 Each toilet seat above mentioned is provided with a guard board 12 of aluminum connected to the hinged cover of the seat by means of chains 54 fastened to the ends of aluminum rod 55 which is soldered to said 30 cover, so that when said cover is raised the board or guard 12 will be raised up close to the bottom of the bowl, preventing water splashing up through the bowl. When the cover is lowered the chains 55 will slack and 35 allow 12 to drop by gravity close to the surface of the sea water where it will be washed by waves splashing on it.

Rubber tubing 56 is fastened to the top 40 of the rib 2 surrounding the chains 54 respectively to prevent the splashing of water up through the holes through which the said chains pass.

45 By providing two toilets at one point and making one of them accessible from one compartment of the boat and the other accessible from the other compartment, I adapt them to the use of persons of different sexes without interference or embarrassment, although a single sheet of metal may be used for the 50 toilet casing and the structure of the toilets collectively is exceedingly compact and simple. The partition which makes the two compartments also supports the toilets and provides an outlet for their discharge, thus 55 fulfilling three functions. I am well aware that toilets have been described in patents as used in life boats; but such boats have not had the special advantageous features adapted to and combined with the toilets as 60 herein described and claimed.

Having thus described my invention, what I claim as new and desire to secure by Letters Patent is:

1. A boat having an outer hull and an inner hull and provided with bracing and 65 spacing bars located between said hulls and with two pairs of upright additional brace bars attached to the inner side of said inner hull respectively near the bow and stern of the boat, co-operating with the before mentioned bars to strengthen said inner hull and in addition providing bearings substantially as set forth. 70

2. A boat provided with two cork pontoons, pivoted arms attaching them to said 75 boat and pawls and ratchets, drums controlled thereby and means wound on said drums for normally holding said pontoons on the water at the sides of the boat, the said arms permitting the pontoons to be 80 raised above the boat for convenience of stowing on shipboard.

3. A boat provided with cork pontoons, means of attachment of said pontoons to said boat, permitting the said pontoons to 85 rest on the water or be raised above the boat at will, rotary drums carried by said boat, pawls and ratchets controlling the rotary adjustment of said drums and chains attached respectively to said drums for winding thereon said chains, which are passed over said pontoons and attached to the boat so that they will hold the said pontoons in position on the water when said chains are tightened by said pawl and ratchet, but will 95 release said pontoons for raising when said pawl and ratchet are released. 90

4. A boat provided with cork pontoons, means of attachment of said pontoons to said boat, permitting the said pontoons to rest on 100 the water or be raised above the boat at will, rotary devices carried by said boat, means for locking said devices at any point of rotation or freeing them at will, and flexible elements arranged to be wound on said devices and drawn taut to hold said pontoons in normal position or freed by said means for raising above the boat. 105

5. A boat divided longitudinally into two compartments by a raised inverted trough 110 or hollow partition and provided with means of propulsion in said trough and a pair of toilets mounted on said trough distant from said means of propulsion, said toilets facing their respective compartments 115 and discharging through the interior of said trough.

In testimony whereof, I have signed my name to this specification.

JULIUS D. BERNSTEIN.
